UNITED STATES PATENT OFFICE.

EDGAR W. CLEVELAND, OF HOLLAND, MICHIGAN.

ADJUSTABLE ARM FOR MULTIPLE-SPINDLE DRILLS.

1,316,141.

Specification of Letters Patent. Patented Sept. 16, 1919.

Application filed March 12, 1919. Serial No. 282,224.

To all whom it may concern:

Be it known that I, EDGAR W. CLEVELAND, a citizen of the United States of America, residing at Holland, in the county of Ottawa 5 and State of Michigan, have invented certain new and useful Improvements in Adjustable Arms for Multiple-Spindle Drills; and I do hereby declare the following to be a full, clear, and exact description of the 10 invention, such as will enable others skilled in the art to which it appertains to make and use the same.

This invention relates to adjustable drill carrying arms for multiple spindle drills 15 and is particularly concerned in the provision of a very simple and novel form of adjustable connection between the arm and the journal box in which the drill spindle is rotatably mounted. This invention is a specific form or modification under the generic 20 invention claimed in my copending application Serial Number 282,223, filed March 12, 1919. Drill carrying arms of this character are mounted in numbers on a common head in 25 a multiple spindle drill and are often adjusted so that the drills are placed closely together. Moreover, the drills may be and usually are of different lengths and it may be desirable to have the different drills 30 operate to different depths in the work, this requiring that the drill be mounted so as to be vertically adjustable with respect to the arm to care for these conditions, the arm itself not having any vertical adjustment with respect to its supporting head. A 35 journal box in which a drill is rotatably mounted to turn about a vertical axis is, accordingly, adjustably mounted at an end of each arm and means must be provided to 40 permit this adjustment and securing of the box in fixed relation to the arm in any of the positions to which it may be adjusted. Usually this is done by bolts, one of which must have its tightening nut located within 45 the arm and in practically inaccessible position, while the other is at a lower position, readily accessible. The invention comprises novel combinations and arrangements of parts such that a tightening or loosening of 50 the lower bolt simultaneously effects a like tightening or loosening of the upper bolt,

whereby adjustment of and securing of the journal box in any desired position with respect to the arm is accomplished through manipulation of the lower bolt only. Actu- 55 ally, the same result may be had by manipulation of the upper bolt only in like manner, though in practice this is not done due to the inaccessibility of the upper bolt for tightening or loosening the same. 60

The construction by means of which I have accomplished this end is illustrated in the accompanying drawing, in which,

Figure 1 is a section taken longitudinally and centrally of the arm, the drill journal 65 box being also shown in section.

Fig. 2 is a horizontal section taken substantially on the line 2—2, of Fig. 1.

Fig. 3 is a view similar to Fig. 1 illustrating a modified form of construction, 70 and

Fig. 4 is a vertical section taken substantially on line 4—4, of Fig. 3.

Like reference characters refer to like parts in the different views of the drawing. 75

The arm is made up of two spaced apart sides 1 having integral ends 2 and 3, against the latter of which the journal box is located. End 3 has openings or slots 4 therethrough and above and below the upper and lower openings the metal making the end 3 is thicker than between the openings forming shoulders 5 as shown. The journal box 6 and the adjacent end of the arm are machined on contacting surfaces so that a smooth and close fit is made. A T-slot 7 is made in the side of the journal box next to the end 3 of the arm and T-bolts 8 have their heads 9 located in the slot, the bolts passing through bushings 10 which enter 80 the openings 4 and which are formed with projections 11 at their inner ends each cut with a bevel or incline 12 as shown. The projection 11 on the upper bushing extends downwardly and that on the lower bushing 85 extends upwardly so that the two projections extend toward each other. Between the same a bar 13, preferably of stock square in cross section, is placed, lying against the inner side of the end 3 of the arm, and beveled 90 at its ends and at its inner side so as to fit against the inclines 12 on the projections 11. 95 100

A nut 8^a is threaded on to the end of each bolt 8 and against the end of the bushing 10 through which the bolt passes.

The drill spindle 14 is mounted in the journal box 6 to turn about a vertical axis, being equipped with a socket member 15 at its lower end below the box into which the drill may have its upper end inserted in the usual manner.

With this structure, a loosening of the nut 8^a on the lower bolt 8 permits the lower bushing 10 to move along the bolt so that the projection 11 on said lower bushing moves away from the lower end of the bar 13, whereupon the bar may drop slightly, this freeing the upper bushing and bolt so that a free movement of the heads 9 in the slot 7 may take place, and the box 6 moved to any desired position, after which tightening of the lower nut 8^a forces the lower bushing in and wedges the ends of the bar 13 against the inclined sides 12 of projections 11, there being a simultaneous tightening of the bolts on tightening the one nut. This operation is easily accomplished and a quick and ready change of position of the journal box with reference to the arm may be had. The shoulders 5 sustain the pressure which may be transmitted from the ends of the rod 14 and a firm and stable arrangement of parts is provided which is durable and has no parts liable to get out of order. Comparatively little machining is necessary also whereby the cost of manufacture is at a minimum.

In Figs. 3 and 4, a slightly modified form of the invention is shown, the bushings 10 being replaced by sleeves 16 fitted into cylindrical openings through the end 3 of the arm. At the inner ends of the bushings heads 17 are located having conically shaped sides, the bolts 8 passing through said heads having the inclined ends of the bar 14 bearing thereagainst as shown and each head having an annular lip extending therefrom into the end of its associated bushing to properly locate and hold the heads in position. The bushings may be slotted to receive the ends of the bar 13 as shown. This construction operates to produce the same general result as described with reference to the construction illustrated in Figs. 1 and 2 and is of value thereover chiefly in lessening the manufacturing cost, the bushings 16 and heads 17 being made very cheaply, being made on automatic screw machines, while the forming of the bushings 10 with their projecting parts 11 is a more expensive machining proposition.

With both forms, however, the release of the journal box for adjustment is effected by loosening the nut on the lower bolt, while the fixing of the same on the arm follows from tightening the same nut only. The simplicity of structure and operation thereof

are valuable features of the invention as is evident.

I claim:

1. An adjustable arm for multiple spindle drills, comprising an arm, a journal box positioned at and against one end of the arm, upper and lower connecting devices for attaching the box to the arm, and a vertically movable member carried on the arm between said devices and moving vertically to tighten or loosen the upper connecting device as the lower connecting device is tightened or loosened, substantially as described. 70

2. An adjustable arm for multiple spindle drills, comprising an arm, a journal box positioned vertically at and against one end of the arm, upper and lower connecting devices for attaching the box to the arm, said box being vertically movable with respect to said connecting devices, and a vertically movable member carried on the arm between said devices and moving vertically to tighten or loosen either of the connecting devices when the other is tightened or loosened, substantially as described. 75

3. An adjustable arm for multiple spindle drills, comprising an arm, a journal box positioned vertically at and against one end of the arm, said box having a T-slot located vertically in the side next to the end of the arm, T-bolts located one over the other having their heads located in the slot and their shanks extending through the end of the arm, a bushing through which each bolt passes, a projection having an inclined side extending downwardly from the upper bushing, a similar projection extending upwardly from the lower bushing, a bar disposed between the bushings and having its ends cut to seat against the inclined sides of the projections on said bushings and lying at one side against the end of the arm, and nuts on the ends of the bolts to bear against the bushings, substantially as and for the purposes described. 90

4. An adjustable arm for multiple spindle drills, comprising an arm, a journal box located in vertical position against an end of the arm, bolts for attaching the box to the arm, said box and bolts having means of connection whereby the box may be adjusted to different positions with respect to the bolts when said bolts are loosened, bushings through which the bolts pass, said bushings being carried by the arm, a bar disposed against the end of the arm on the side thereof opposite to that against which the journal box rests, nuts on the ends of the bolts, and means on the bushings engaging with the ends of the bar for simultaneously tightening or loosening both bolts as the nut on one of the bolts is tightened or loosened. 105

5. An adjustable arm for multiple spindle drills, comprising an arm, a journal box located in vertical position against an end of 110

the arm, bolts for attaching the box to the arm, interengaging means between the bolts and box whereby the box may be adjusted to different positions when the bolts are loosened, a bar positioned vertically against the end of the arm on the side thereof opposite the side against which the journal box is positioned, said bar having its ends at one side cut at angles to the length of the bar

and oppositely to each other, and means on the bolts to engage with said inclined ends of the bar as the bolts are tightened and force the bar against said means whereby tightening of one of the bolts simultaneously tightens the other, substantially as described.

In testimony whereof I affix my signature.
EDGAR W. CLEVELAND.
